J. KAUFMAN

COMBINED CASE AND RAZOR HOLDER

Filed July 17. 1924

INVENTOR
BY Joseph Kaufman
William S. Gluck
ATTORNEY

UNITED STATES PATENT OFFICE.

JOSEPH KAUFMAN, OF NEW YORK, N. Y., ASSIGNOR TO AMERICAN SAFETY RAZOR CORPORATION, OF NEW YORK, N. Y., A CORPORATION OF VIRGINIA.

COMBINED CASE AND RAZOR HOLDER.

Application filed July 17, 1924. Serial No. 726,485.

My present invention relates generally to containers and more particularly to an arrangement whereby a container for a razor and a cigarette case can be so associated that the cigarette case forms the shipping display and sales package for the razor container.

In order to permit of the shipment, proper display and convenient sale of razors, particularly of the separable safety type, it has been the custom generally hitherto, to provide a container for the razor which not only was made to serve its utilitarian functions as a container, but also was constructed so as to be extremely attractive as well as attracting, and as a result of this, the cost of this container was a great deal in excess of what is required from the standpoint merely of utility, and this cost, it has been found by actual calculation, is far in excess of that justified by merely the value of the box from the standpoint of attraction.

One of the important objects of my invention is to provide with a receptacle for a safety razor which will serve adequately as such while it is in actual use as a razor, a container which, in addition to presenting all of the desirable factors hitherto present in such containers from the standpoint of shipment, display, etc., can be given by the purchaser a use wholly independent and apart from its use as a razor container, and which additional utility and function fully justifies the additional expenditures disbursed therefor.

Another object of my invention is the provision with a receptacle for a safety razor of a container which takes the form of a conventional cigarette case and which container can be so employed, without impairing the function of the receptacle for its intended and desired purposes.

My invention further provides a receptacle for a safety razor so constructed and arranged as to permit of it being received, contained and effectively held within a conventional type of cigarette case.

My invention further provides a novel, simple, efficient and economical receptacle for a razor made wholly of metal stampings.

For the purpose of attaining these objects and such other objects as may hereinafter appear or be pointed out, I have illustrated in the drawings, one embodiment of my invention wherein—

Fig. 1 is a perspective view of my razor containing receptacle positioned within a more or less conventional type of cigarette case.

Fig. 2 is a top plan view looking down upon the receptacle for receiving the razor parts and accessories.

Fig. 2^a shows the blank from which the body portion of the receptacle is formed;

Fig. 3 is a vertical section taken on line 3—3 of Fig. 2;

Fig. 4 is a section taken on line 4—4 of Fig. 3; and

Fig. 5 shows the cigarette case used in its ordinary conventional way.

Upon viewing Fig. 2 of the drawing, it will be observed that my razor containing receptacle comprises generally two compartments 10 and 11 connected in spaced relation by the web 12, the compartments being closed at their ends by the end pieces 13 and 14.

The intermediate or body part of this receptacle of Fig. 2 is formed from a single blank shown in detail in Fig. 2^a of the drawing, wherein it will be observed the blank has its central portion cut away altogether to provide the opening as shown at 50 for purposes that will be understood. The blank is made up of the intermediate sections 16 and 17 which extend transversely of and preferably coterminously with the cut away portion 50, the end wall sections 18 and 19 on one side of the blank and the end wall sections 20 and 21 on the other side, these end wall sections being provided with the flanges 22, 23, 24 and 25 respectively for purposes that will appear. The intermediate end sections 26 and 27 of this blank are curved at their outer edges as shown and are intended to form the bottom of the compartments 10 and 11 and for purposes of attachment are provided along their curved edges with the flanges 51 and 52. The intermediate side sections 16 and 17 are provided respectively, one with the cut out or opening 40 and the other with the portion cut along three sides to form the tab 41 to cooperate with the opening 40 in a manner also to be pointed out.

The blank illustrated in Fig. 2^a is formed into the intermediate body position of the receptacle shown in Fig. 2 as follows:—

The intermediate side sections 16 and 17

are shaped preferably by a stamping operation to form the walls 30, 31 and 32 from the one wall section 16 and the walls 33, 34 and 35 from the other wall section 17, as more clearly shown in Fig. 2 of the drawing. The part of the blank of Fig. 2^a above the line A—A and including the walls 16, 18 and 20 are now bent upwardly along this line A—A to a position substantially at right angles to the bottom sections 26 and 27, and the wall sections 17, 19 and 21 are similarly bent up into parallelism with the wall sections on the other side along the line B—B and with the parts properly dimensioned the walls 31 and 34 will be in parallelism and adjacent each other, as shown in Fig. 2 and the tab section 41 will be substantially in registry with the opening 40, to permit of the tab 41 being passed through the opening 40 and then bent down as more clearly shown in Fig. 4 of the drawing, thus securely connecting the two walls 31 and 34 of the main body member to form the web section 12 of Figure 2.

From the description thus far given, it will be observed that I form as the body portion of the receptacle, the walls 18, 19, 30 and 33 and the bottom 26 delimiting the major part of the compartment 10 and the walls 20, 21, 32, 35 and the bottom 27 delimiting the major part of the compartment 11.

The end members 13 and 14 to complete the receptacle walls are preferably in the form of curved members having their free edges so as to be received within the flanges 22, 23, 24 and 25, (see Figure 2^a) which have been channeled for this purpose as clearly shown in Fig 2 of the drawing, and the flanges 51 and 52 at the bottom members 26 and 27 are bent upwardly and curved to the curvature of the members 13 and 14 and are positioned immediately exterior thereof. The walls 13 and 14 may be secured fixedly in the position shown in Fig. 2 in any desired or preferred manner, as by soldering, brazing, etc.

From the description thus far given, it will be observed that I have in this manner formed a receptacle which is made up of two spaced compartments between which is a web 12 positioned preferably centrally of the width of the compartments, so that there is provided between the compartments and on each side of the receptacle, the spaces defined by the walls 30, 31 and 32 and the walls 33, 34 and 35 respectively, the purpose of which will now be pointed out.

In Figs. 1 and 5 of the drawing, I have shown a more or less conventional type of cigarette case and holding means therein, which on the illustrated embodiment is made up of two substantially similar halves 60 and 61 so shaped as to provide a substantial space therebetween when closed, the two halves being hinged together as shown at

62, there being a spiral spring 63 about the hinge pin, the ends 64 and 65 of this spring pressing respectively down upon the finger members 66 and 67 which are also hinged about the hinge pin in any preferred or desired manner as by the hinge members 68. In this manner, these holding fingers 66 and 67 are each held within its respective section and pressed downwardly therein. The receptacle for containing the razor parts and accessories illustrated in Fig. 2 has been so dimensioned and constructed that when positioned within the cigarette case as shown in Fig. 1, the spaces provided between the compartments 10 and 11, as has already been described, will be positioned in registry with these fingers 66 and 67 so that even though the height of the receptacle of Fig. 2 may be greater than the depth of either of the halves 60 or 61, such receptacle can be conveniently received within the cigarette case when the case is closed because of the fact that the fingers 66 and 67 are received within one of the spaces referred to. Furthermore, by making the receptacle in Fig. 2 symmetrical in all respects, that is by providing similar spaces on opposite sides of the web 12 and between the compartments 10 and 11, this receptacle can be received within the case in reversed positions, so that any particular manner of association of the two is not necessary, except that the compartments 10 and 11 shall be positioned on opposite ends of the case of Fig. 1, in which figures are shown, parts of the safety razor as well as the blades received within the receptacle.

From the description thus far given, it will be observed that I have not only provided a simple, economical and efficient receptacle for holding the parts of a razor and also the blades, but have so constructed and devised this receptacle, that it can be conveniently received within the conventional type of cigarette case. As a result of this, the cigarette case itself serves as the container for the safety razor and the safety razor receptacle, so as to permit of the receptacle and its contents being shipped, displayed and sold not only in a convenient way and packed in an attractive case, but when in the hands of a consumer, the safety razor receptacle, as shown in Fig. 1, can be removed from the cigarette case and the cigarette case thereafter used solely as a cigarette case, or alternatively, the parts can be so constructed, that the section 61 for instance, can serve to hold cigarettes along with the shaving razor receptacle contained therein.

While I have set forth the steps employed for forming the body of the receptacle from the blank of Fig. 2, it will be understood that this is merely illustrative, both as to the number of steps employed, their character and their sequence.

Having thus described my invention and illustrated its use, what I claim as new and desire to secure by Letters Patent is—

1. A receptacle for containing razor parts and accessories and adapted to be received and contained within a conventional cigarette case of a type which is provided with a holding means extending across the interior thereof, said receptacle having a space 10 exteriorly thereof and intermediate its ends within which is adapted to be positioned said holding means whereby the receptacle will be held in predetermined position by said holding means.
- 15 2. A receptacle for containing razor parts and accessories and adapted to be received and contained within a conventional type of cigarette case of a type which is made up of pivoted container sections, at least one of 20 which is provided with a holding means extending across the inside thereof, said receptacle being of a height greater than that of said container section and having a space exteriorly thereof and intermediate its ends 25 within which said holding means is positioned whereby the receptacle can be held in predetermined position by said holding means.
- 30 3. A receptacle for containing razor parts and accessories, and adapted to be received and contained within a conventional type of cigarette case of a type which is made up of pivoted container sections, at least one of 35 which is provided with a holding means extending across the inside thereof, said receptacle being of a height greater than that of said container section and having spaces 40 on opposite sides and exterior thereof intermediate its ends, within either of which spaces, said holding means is positioned whereby the receptacles can be held predeterminedly in reversed positions by said holding means.
4. A receptacle for containing razor parts and accessories, and adapted to be received 45 and contained within a conventional type of cigarette case of a type which is made up of pivoted container sections, with a holding means extending across the inside thereof, said receptacle being of a height greater 50 than that of said container section and said receptacle comprising spaced compartments so arranged that when the receptacle is positioned within the cigarette case, the space between the compartments will be in registry 55 with, and will receive therein the holding means.
5. A blank to form the side walls, the bottom and one end wall of each of a plurality of spaced compartments, and also the connecting means therefor, said blank having its center cut away, whereby the portion of the blank extending transversely of this cut away portion can be shaped to form the 60 said end walls for the compartments and 65 also the means connecting the compartments.
6. The process of forming the body portion of a plurality of spaced connected sections, from a blank having its central portion cut away, said process including the 70 steps of shaping each of the portions of the blank transversely of and coterminous with the cut away portion into parallel walls, and a connecting section, and then bending the blank along lines in registry with the 75 longitudinal delimiting lines of the cut away portion, whereby said end walls so formed are brought in registry with each other so as to form one of the end walls of each compartment, and the connecting sections are 80 brought into parallelism, to form the means for connecting the sections.

In witness whereof, I have hereunto signed my name.

JOSEPH KAUFMAN.
